U.S. Appl. No. 29/387,517, filed Mar. 14, 2011, Krueger.

(Continued)

Primary Examiner — Susan Moon Lee(74) *Attorney, Agent, or Firm* — Poisinelli PC**CLAIM**

I claim the ornamental design for a fill component of a bird feeder, as shown and described.

DESCRIPTION

FIG. 1 is a front perspective view of a fill component of a bird feeder showing our new design;

FIG. 2 is another front perspective view thereof;

FIG. 3 is a side perspective view thereof;

FIG. 4 is bottom side view thereof;

FIG. 5 is a side elevation view thereof;

FIG. 6 is a top plan view thereof; and,

FIG. 7 is a bottom view thereof.

The broken line showing of a cylindrical bird feeder body with ports depicted in FIG. 1 is not claimed.

1 Claim, 7 Drawing Sheets# US D698,502 S
